OTHER PUBLICATIONS

The design of this watch builds on a design previously submitted by the same inventor in U.S. Appl. No. 29/288,184, filed Jun. 4, 2007.

* cited by examiner

Primary Examiner—Lucy Lieberman

(57) **CLAIM**

The ornamental design for a watch, as shown and described.

DESCRIPTION

FIG. 1 is a front perspective view of a watch showing our new design;

FIG. 2 is a front elevation thereof;

FIG. 3 is a rear elevation thereof;

FIG. 4 is a right side elevation thereof shown with the watch in an inverted position;

FIG. 5 is a left side elevation of the watch; and,

FIG. 6 is a bottom view of the watch.
